(57) **CLAIM**

The ornamental design for a plasma bottle for rapid freezing, as shown and described.

DESCRIPTION

FIG. 1 is a perspective view of a plasma bottle for rapid freezing showing our new design;

FIG. 2 is a front elevation view of the plasma bottle of FIG. 1; FIG. 3 is a rear elevation view of the plasma bottle of FIG. 1; FIG. 4 is a right side elevation view of the plasma bottle of FIG. 1;

FIG. 5 is a left side elevation view of the plasma bottle of FIG. 1;

FIG. 6 is a top plan view of the plasma bottle of FIG. 1; and, FIG. 7 is a bottom plan view of the plasma bottle of FIG. 1. The broken lines in the figure drawings represent portions of the article and form no part of the claimed design.
